UNITED STATES PATENT OFFICE

LAWRENCE O'ROURKE, OF SAN FRANCISCO, CALIFORNIA

INSULATING HOLDER FOR COOPER-HEWITT TUBES AND INERT GAS TUBES GENERALLY

Application filed June 1, 1931. Serial No. 541,258.

The present invention relates to improvements in insulating holders for Cooper-Hewitt tubes and inert-gas tubes, generally.

The present practice, as is well-known, is to support the glass-body of these tubes near their extremities in metal holders covered by heat-resisting insulating material, the extremities of these holders being bent to form feet fitted to the contour of the body of the reflector and provided with holes adapted to register with other holes borne by the body of the reflector, to which they are secured by small bolts and nuts, the holders, as thus provided, being grounded. Since these tubes are not infrequently exposed to the weather, the present insulation proves anything but complete, and, in rainy weather particularly, most unsatisfactory.

The purpose of the present invention is to provide a holder for such tubes wholly constituted of an insulating material and so formed and secured to a reflector body as to afford perfect insulating support to all such tubes under all weather conditions.

Any insulating material possessed of high insulating qualities and the necessary strength and rigidity may be employed in the construction of my holders.

With my brackets, or holders, the present practice is departed from, in that the support is removed from the glass tube and transferred to the metal portions of the electrode and terminal sections. In these positions, they are removed to less heated points and relieved of the necessity of grounding to carry off leakages.

In the accompanying drawing, forming a part of this specification, and in which like characters of reference refer to similar parts, throughout:

Figure 1 is a view of a reflector member bearing a tube of the usual Cooper-Hewitt construction supported by my insulating brackets, as carried by said reflector;

Figure 2 is a detail of a bracket adapted for the accommodation and support of the metal portions of a pair of electrode-terminal sections as borne by the two reduced extensions of a Cooper-Hewitt tube and therethrough the forward end of this tube.

Figure 3 is an edge view, of the bracket shown in Figure 2, showing the two arms, the curved base and the character of the two bearings carried by the respective extremities of these arms for the reception of the respective electrode-terminal sections;

Figure 4 is a detail of one of the arms of the double-armed bracket, showing a hinged section as borne by an extremity and adapted to support the metal portion of an electrode-terminal section; and

Figure 5 is a detail of a modified bracket, or holder, showing its curved base, its body, the upper portion of this body as provided with a semi-circular bearing, the hinged section as borne by the upper body portion, and the means for securing the one to the other in fixed relation, when enclosing and supporting the metal section of an electrode-terminal section.

Referring more particularly to the drawing, the numeral 6 indicates a reflector member to which are attached in spaced relation a pair of my insulating brackets, or holders, 12 and 13, supporting in insulated relation a Cooper-Hewitt tube 18.

The brackets 12 and 13 differ in their construction.

The bracket 12 comprises a curved base 12' provided with bolt-openings 11 and 11' and two similar supporting arms 7 and 7', each of which is equipped with semi-circular seats and hinged recessed sections 8 and 8' adapted, when in closed relation with the terminal sections of the arms 7 and 7', to form circular openings 10, as indicated in Figure 4, these being respectively provided with bolt-openings 27 and 27' for the accommodation of bolts provided with nuts similar to that shown at 9, their purpose being to retain in locked relation the sections 8 and 8' with the extremities of the arms 7 and 7'.

The bracket 13 has also a curved base 17 provided with bolt-openings 16 and 16' and a body portion 13' extending right-angularly from the front edge of said base and terminating in a semi-circular seat 25 and a section 14 hingedly secured thereto, as indicated at 15, and bearing a semi-circular recess 25' adapted to form a complete circle with 25

when brought into normal relation therewith, the section 14 being also provided with a bolt-opening 24 adapted to register with the bolt-opening 23 borne by the body portion 13', in 5 the which position of registration a bolt and nut, similar to 15, serves to hold them in this relation.

The tube, or glass-body, 18, whose insulated support in spaced relation to the reflector 10 member 6 is thus provided for, is, as here illustrated, of the ordinary Cooper-Hewitt type, and comprises a glass-body 18 provided with a mercury volatilizing chamber 18', carrying the usual resistance heating element, 15 the two right angularly extending divergent body extensions thereof 26 and 26', the two electrode-bearing members 21 and 21' carried, respectively, by said divergent body extensions, the wires 20 and 20' leading respectively 20 to said electrode-bearing members, and the electrode-bearing member 22, with the wires 19 and 19' leading thereto, the former representing the anode, and the latter the cathode of the electric system.

25. In the installation of the tube 18 in insulated relation with the reflector member 6, the simpler, and preferred, plan is to first bolt the two insulating brackets, or holders, 12 and 13 to the concave surface of the reflector 30 member 6, by means of screw-headed bolts and nuts. After thus securing the insulating brackets 12 and 13, the hinged members 8, 8' and 14 borne by the respective extremities of these brackets are thrown back, leaving 35 their concavities as open seats to receive the metallic electrode-bearing members 21, 21' and 22. With the tube 18 thus placed and supported, the hinged members 8, 8' and 14 are returned to closed positions thereabout and 40 there retained by the insertion of screw-headed bolts, of the character indicated at 15, in Figure 5, into the indicated bolt-openings and there secured by setting-up the nuts provided therefor.

45. Having thus described my invention, I claim and desire to secure by Letters Patent of the United States:

1. An insulating bracket comprising a curved base bearing bolt-openings, a body 50 portion extending right-angularly from the front edge of said base and ending in a semi-circular seat having upon its either side and adjacent thereto a bolt-opening, and a section bearing a semi-circular concavity having 55 bolt-openings upon either side thereof and adjacent thereto and adapted to register with the aforementioned bolt-openings for the accommodation of retaining bolts, said section being hingedly connected to the semi-circular 60 seat section borne by the body portion, one of said bolts serving as a hinge pintle and the other as a locking means.

2. An insulating brackets comprising a curved base bearing bolt-openings, two similar body portions, each of which is formed-

up from an extremity of said base at an angle of less than 90° thereto, the extremity of each of said body portions terminating in a semi-circular seat having upon its either side and adjacent thereto a bolt-opening, and a hinged section bearing a semi-circular concavity having bolt-openings upon either side thereof and adjacent thereto and adapted to register with the aforementioned bolt-openings for the accommodation of screw-headed bolts, said section being hingedly connected to the semi-circular seat section borne by the body portion, one of said bolts serving as a hinge pintle and the other as a locking means therefor.

In testimony whereof I hereunto affix my signature.

LAWRENCE O'ROURKE.
